UNITED STATES PATENT OFFICE.

EDWARD E. FOSTER, OF BEVERLY, MASSACHUSETTS.

CAM-PATH-GENERATING MACHINE.

1,256,461.

Specification of Letters Patent. Patented Feb. 12, 1918.

Application filed October 24, 1913. Serial No. 797,079.

To all whom it may concern:

Be it known that I, EDWARD E. FOSTER, a citizen of the United States, residing at Beverly, in the county of Essex and State of Massachusetts, have invented a new and useful Improvement in Cam-Path-Generating Machines, of which the following is a specification.

The present invention relates to machines 10 for generating cam paths.

Heretofore it has been customary in the manufacture of barrel cams to plot the cam path upon paper and then scratch the generated cam path upon a rectangular sheet of 15 zinc which is then wrapped or developed about a cylindrical piece of cast-iron. The cylinder is then cut down to the inner working surface of the cam path after which the cylinder is inserted into a cam cutting machine 20 where it directs the operation of the cutting tool. As a cam may actuate a follower with a harmonic motion, a uniform motion or a gravity motion the plotting of a path for a barrel cam requires considerable knowledge, skill and experience upon 25 the part of the designer.

The object of the present invention is to produce a machine by which a barrel cam path may be accurately generated by an operator having little or no training in the 30 design of cams.

To the accomplishment of this object, and such others as may hereinafter appear, the features of the invention relate to certain 35 devices, combinations and arrangements of parts, hereinafter described and then set forth broadly and in detail in the appended claims, which possess advantages which will be apparent to those skilled in the art.

40 The various features of the present invention will be best understood from an inspection of the accompanying drawings illustrating a machine for generating a barrel cam path for imparting harmonic motion to a reciprocating follower in the best form at present known to me, in which,

Figure 1 is a perspective of the machine,

Fig. 2 is a sectional elevation of the crank for reciprocating the tool, and

50 Fig. 3 is a sectional elevation of the tool carrier and its associated parts.

In the illustrated embodiment of the invention the cam path is generated directly upon a leader by a tool which is rotated to 55 scribe a circle upon the leader having a diameter substantially equal to the diameter

of the follower employed with the cam. The leader is reciprocated to transfer the point of operation of the tool along the leader and the tool is reciprocated transversely to the 60 path of reciprocation of the leader to change the direction of the path scribed by the tool upon the leader. The tool is reciprocated by a crank in the specific form of the invention selected for the purpose of illustration and 65 consequently a cam path for imparting a harmonic motion to the cam follower is generated. It will be apparent to those skilled in the art, however, that mechanism for reciprocating the tool with either a uniform 70 or a gravity motion may be substituted for the crank. In order to adapt the machine for generating any desired cam path adjustments are provided for varying the operation of the tool in accordance with variations in the base circles, rises, drops, dwells and times in the different forms of cams to be 75 designed. The leader, which is preferably a rectangular sheet of zinc, is clamped on a leader support 1 with one edge engaged 80 with a shoulder 2 formed on the leader support. The support 1 is mounted to slide on ways 3 carried by a shelf 4 projecting from a table 5 supported by legs (not shown). The support 1 carries a rack 6 which is engaged 85 by a gear 7 carried upon the upper end of a vertical shaft 8 which is journaled at one end in a boss 9 suitably bored in the table 5 and at the other end in a step bearing 10 formed in a sleeve 11 loosely mounted 90 on a horizontal shaft 12 journaled in bearings depending from the table 5. The shaft also carries a bevel gear 13 which meshes with a gear 14 carried by the shaft 12 and also with a gear 15 carried by a sleeve 16 95 loosely mounted on the shaft 12. Secured to the sleeve 16 is a disk 17 which is provided with an index 18 on its periphery co-operating with a pointer 19 secured to an overhanging bracket 20 carried by the table 100 5. The index is graduated in degrees and the gears 13, 14 and 15 are proportioned to impart a complete rotation to the gear 7 when the disk 17 is rotated to transfer the pointer 19 one complete revolution around 105 the periphery of the disk 17. The gear 7 is proportioned to transfer the point of operation of the scratching tool to be described from one lateral edge of the leader to the other lateral edge during one complete revolution. Splined to the shaft 12 is a second disk 21. The backs of the disks 17 and 21

rotate in engagement with rolls 22 (only one of which is shown) which hold the disks pressed toward each other.

In order to scratch a cam path upon the leader carried by the support 1 the machine is provided with a scratching tool 24 which is held by a screw 25 in a block 26 carried by a carrier 27. The carrier 27 is secured to a sheave 28 carried by the lower end of a vertical shaft 29 which is rotatably mounted in a chamber 30 formed in a frame 31. The frame 31 is secured to a horizontal rod 32, mounted to reciprocate in the bracket 20, by a clamping bolt 33. The sheave 28 is driven from some suitable source of power so that the tool may be rapidly driven to scratch a circle upon the face of the leader. As the diameter of this circle is substantially equal to the width of the cam path, or the diameter of the cam follower, provision is made for adjusting the tool to scratch different sizes of circles in accordance with the different widths of cam paths to be generated. To this end the block 26 may be adjusted in ways formed on the carrier 27 in a path transverse of the axis of rotation of the shaft 29. With this construction the tool 24 may be actuated to form a point upon the leader when the tool is adjusted in line with the axis of the shaft 29, or may be actuated to scratch a circle having a diameter equal to the length of the carrier 27 when the tool is placed at one end of the carrier 27. To serve as a guide for the adjustment of the block 26 on the carrier 27 the carrier is provided with an index 34. The adjusted position of the tool 24 on the carrier 27 is maintained by a clamping screw 35 arranged to bind the block 26 on the ways of the carrier 27. The tool 24 is pressed against the face of the leader by a spring 36 which is interposed between the top of the shaft 29 and the end of the chamber 30. In order to elevate the tool 24 against the tension of the spring 36 the frame 31 carries a horizontal shaft 37 one end of which is provided with a knurled knob 38 and the other end of which carries an eccentrically mounted pin 39 arranged to engage a groove 40 formed in the shaft 29. With this construction a turn of the knob 38 elevates the tool from the face of the leader. To hold the tool elevated the frame 31 carries a spring plunger 41 which engages a groove 42 formed in the shaft 37.

With the construction so far described a reciprocation of the leader will transfer the point of operation of the tool along the leader. In order to shift the point of operation of the tool during the reciprocation of the leader so as to change the direction of its path the rod 32 is connected to a yoke 43 mounted to slide upon guides 44 carried by the bracket 20. The yoke 43 embraces a rectangular block 45 which is swiveled upon

a crank pin 46 slidably mounted in a slot 48 formed in a platform 49. The platform is secured to the upper end of a vertical shaft 50 the upper end of which is journaled in a bearing carried by the bracket 20 and the lower end of which is journaled in a step bearing 51 carried by the shaft 12. The crank pin is mounted on a block 52 which slides in ways 53 formed in the platform 49. To hold the block 52 in any desired position of adjustment it carries a bolt 47 by means of which the crank pin 46 and block 52 may be clamped to each other and to the platform 49. With this construction the tool 24 is reciprocated toward and from the axis of the leader by a crank which is driven by the rotation of the shaft 50. As it is desirable to vary the throw of the crank the upper face of the platform 49 is provided with an index to serve as a guide to the operative in adjusting the yoke 43 and its associated parts nearer to or farther from the axis of the shaft 50. To guide the tool 24 to reciprocate transversely to the path of reciprocation of the leader 1 the bracket 20 carries a horizontal rod 54 arranged in a vertical plane intersecting the axis of the leader. The rod 54 loosely passes through the frame 31 so that the tool may reciprocate freely thereon and thus be constrained to move transversely toward and from the medial line of the leader.

In order to simultaneously reciprocate the leader and the tool the shaft 50 carries a roll 55 the periphery of which engages the opposed faces of the disks 17 and 21. The roll 55 is splined to the shaft 50 and may be adjusted thereon to position the roll at any desired distance between the axes of the disks and the peripheries thereof to vary the speed of rotation of the shaft 50. To this end the roll 55 carries a ring 56 which rotates upon an arm 57 loosely embracing the shaft 50 and projecting from a clamp 58 which is mounted on a vertical rod 59 carried by the bracket 20 and the bearing 51. The rod 59 is provided with an index to serve as a guide for the adjustment of the roll along the shaft 50 by the operative. With this construction when the operative rotates the disk 17 in the direction of the arrow Fig. 1, the leader and tool are simultaneously reciprocated.

In using the machine to generate a cam path intended to impart, for instance, a harmonic rise of 2 inches in 90 degrees, a harmonic drop of 2 inches in 45 degrees, and a dwell during the remaining angle, the frame 31 is adjusted upon the rod 54 so that the distance from the center of the shaft 29 to one longitudinal edge of the leader corresponds to the base circle of the cam path to be generated. The rod 54 is provided with an index to serve as a guide for the operative in adjusting the tool for the

base circles. After this adjustment is made the frame 31 is temporarily held by a screw 60 which clamps the frame 31 to the rod 54. The bolt 33 is then loosened to free the 5 rod 32 and the yoke 43 is then adjusted along the platform 49 until the axis of the swiveled block 45 is one inch from the axis of the shaft 50. This adjustment is made when the platform 49 is positioned so that 10 a mark 61 thereon registers with a mark 62 on the upper face of the bracket 20 at which time the crank is at its limit of movement in one direction. After this adjustment is made the frame 31 is unclamped from the rod 54 and again clamped to the 15 rod 32.

Now it being desired to generate a cam path for imparting to a cam follower a harmonic rise of 2 inches in 90 degrees the 20 roll 55 is adjusted on the shaft 50 to such a point that when the disk 17 is rotated to transfer the pointer 18 from the 0 mark to the 90 mark on the index the roll 55 will rotate one half a revolution and thus rotate 25 the crank from its limit of movement in one direction to its limit of movement in the other direction. The parts being adjusted as described, the operative rotates the disk 17 until the pointer 19 reaches the 90 mark 30 on the index 18. During the rotation of the disk 17 the leader rotates through 90 degrees and the rotating tool 24 is reciprocated away from the axis of the leader thus generating upon the leader a cam path 35 which will impart to a cam follower a harmonic rise of 2 inches in 90 degrees. To obtain a harmonic drop of 2 inches in the next 45 degrees the roll 55 is adjusted to the 45 mark on the rod 59 so that the roll 40 will again revolve a half rotation as the point travels from the 90 mark to the 135 mark on the index 18. Then this disk is again rotated until the 135 mark is reached. During this movement of the disk 17 a cam 45 path is generated on the leader which will impart to a cam follower a harmonic drop of 2 inches in 45 degrees. To obtain a dwell during the remaining angle of 225 degrees the axis of the block 45 may be brought in 50 line with the axis of the shaft 50 so that during the continued rotation of the disk 17 to bring the pointer 19 back to 0 or, stated in another way, to complete the 360 degree rotation of the gear 7 the tool remains stationary upon the rod 54. It is preferred, 55 however, to clamp the frame 31 to the rod 54 and unclamp the frame from the rod 32

to prevent accidental displacement of the tool.

It will be readily apparent that the present invention could be used to generate a cam path cut in a plane as well as a cam path for a barrel cam.

While the machine has been described as generating a specific cam path it will be readily apparent to those skilled in the art that the machine is adapted to generate any cam path for imparting to a reciprocating cam follower either a harmonic motion or a dwell as the machine is provided with the necessary adjustments for varying the operation of the tool upon the leader in accordance with the variations in the base circles, rises, drops and times of the cam paths which it may be desired to generate. 75

While the invention has been illustrated and described in connection with a machine for generating a cam path for imparting harmonic motion to a reciprocating follower it must be understood that this is merely one embodiment of the invention which may have a variety of forms depending upon the kind of motion which it is desired to impart to a follower, the kind of cam to be provided with a cam path, and whether the follower is offset or reciprocates or oscillates. Neither is the specific construction and arrangement of parts shown and described essential, nor is the conjoint use of all the features of the invention essential, except so far as specified in the appended claims, and it may be varied or modified without departing from the broader features of the invention. 85 90

What is claimed as new is: 95

1. A machine for generating cam paths, having, in combination, a leader support, a tool for scratching the leader, means for imparting rapid circulatory movements of slight amplitude to the tool, mechanism 100 for reciprocating the tool, mechanism for reciprocating the leader support, and a single means for operating said mechanisms, substantially as described.

2. A machine for generating cam paths, 105 having, in combination, a leader support, a rack carried thereby, a gear for driving the rack, a tool, a crank for reciprocating the tool, and means for driving the gear and crank, substantially as described. 110
